MANUFACTURE AND PRODUCTION OF ARTIFICIAL SILK AND APPARATUS THEREFOR

Application filed August 13, 1927, Serial No. 212,846, and in Great Britain October 4, 1926.

This invention relates to the manufacture of artificial silk by the method known as dry spinning, that is to say, the method in which a solution of a cellulose derivative such as a cellulose ester or cellulose ether in a volatile solvent is extruded through fine orifices into a gaseous atmosphere, whereby the solvent is vapourized, leaving the cellulose ester or cellulose ether in the form of filaments. For the sake of clearness we will describe this invention with reference to the manufacture of artificial silk by spinning a solution of cellulose acetate in acetone into an atmosphere of warm air which will become to some extent laden with acetone vapour, before it leaves the spinning chamber, but it will be understood that the invention is not limited to the use of this particular cellulose compound or solvent or evaporative medium, as the term "artificial silk" is intended to include generally all the types of artificial filaments which can be produced by the dry spinning process.

When producing artificial silk from a solution of cellulose acetate in acetone according to the dry spinning method, the character of the silk is liable to vary according to the greater or smaller content of acetone vapour in the air in the spinning chamber, other factors remaining constant. Thus, with a higher proportion of acetone vapour in the neighbourhood of the jet, the filaments are generally more liable to have a flatter cross-section and a greater lustre than when the proportion of acetone vapour is lower. When it is desired to produce one particular quality of artificial silk the conditions as regards the acetone content in the spinning chamber should be kept constant and further such conditions should be maintained as nearly as possible the same in all the spinning chambers in which it is desired to produce the same quality of artificial silk.

We have now found that we are able to maintain constant in a spinning chamber the conditions as regards the acetone vapour content by making use of a chamber provided with a valve or other means for regulating the flow of air into or out of the chamber, and with a katharometer. The said katharometer should comprise two small lengths or coils of wire which are heated by means of an electric current. The two lengths or coils of wire are placed in two arms of a Wheatstone bridge system, so that their resistances can be compared, one of the coils being enclosed in an atmosphere of constant composition while the other is exposed to the action of the gaseous mixture contained in the spinning chamber. According to the content of acetone in the said gaseous mixture, the rate of loss of heat from the said coil will vary, and consequently the difference between the resistance of the coil exposed to the gaseous mixture, and the resistance of the other coil exposed to a constant atmosphere, which difference of resistance can be measured by the Wheatstone bridge method or indicated by means of a galvanometer or other instrument such as is used in connection with a Wheatstone bridge, will enable the operator to ascertain whether the conditions as regards the acetone vapour content are remaining constant in each particular spinning chamber, and also whether such conditions in one spinning chamber are more or less the same as or equal to the conditions obtaining in the other spinning chambers. It is not necessary to ascertain the absolute value of the vapor content but simply an index of whether or not it is varying. The absolute value could, of course, be obtained by proper calibration of the recording instrument. In this case, expressions such as "value of the vapor content" mean either the absolute value, a comparative value or even the mere fact of a variation from standard. Should he find that the conditions have varied from the standard which, at the moment, it is desired to maintain, he will, by making suitable adjustments for instance in the quantity of air entering or leaving the spinning chamber, be able to regulate such amount of air entering or leaving the spinning chamber, so as to bring back again the conditions as regards the acetone vapour content to the standard which is required. The acetone vapour content inside the spinning chamber may, of course, vary according to the conditions used. For instance,

in the spinning of a thread of heavier total denier, while making use of the same strength of cellulose acetate solution, the extrusion of a larger quantity of such cellulose acetate solution will be necessary, with the consequent evaporation of a larger quantity of acetone, so that if it be desired to maintain the actual percentage of acetone in the gas leaving the spinning chamber, the same as when a thread of lower denier is being spun, it will be desirable in the case of the heavier denier to pass a greater current of air through the apparatus.

It will, of course, be understood that the proportion of acetone contained in the air of the spinning chamber differs at different parts of the spinning chamber. For example, in the case in which the spinning nozzle is situated at the top of the chamber so that the threads travel downwards and are taken out at the lower end of the chamber, while the air travels in the opposite direction, that is to say, enters at the lower end and leaves at the upper end of the chamber, if fresh air is allowed to enter the chamber at the lower end, the acetone content just at the point of entry will be practically nil. As this air ascends inside the chamber, it will gradually take more and more acetone from the descending thread, and the acetone content will, consequently, increase, reaching a maximum as it passes the jet where the acetone solution of cellulose acetate is being extruded into the chamber and the evaporation of the acetone commences. In order, therefore, to ascertain whether the conditions as regards the acetone vapour content in the mixed atmosphere of the chamber is remaining constant, it will be necessary in the case in which the katharometer itself is placed inside the spinning chamber, that the said katharometer should remain in one position in the spinning chamber and should not be moved about from place to place in the said chamber. If, however, the katharometer be placed outside the spinning chamber and a part of the acetone-laden air is taken from the chamber and brought to the katharometer, it will be necessary that this acetone-laden air be taken from the spinning chamber under uniform conditions, for instance, it should always be taken from the same place inside the chamber and at the same rate. It is convenient for example to take the air, which is to be brought to the katharometer, from the narrow exit tube which is attached to or forms the upper part of the spinning chamber, since here the mixture of air and acetone vapour is practically uniform and represents the average composition of the gaseous contents of the spinning chamber. Similarly in order to ascertain whether the conditions obtaining in one spinning chamber are similar to those of another spinning chamber or other chambers of the jet or series, it is desirable

that the katharometers should be placed in approximately the same position in each of the spinning chambers or that the acetone-laden air to be tested should be taken under similar conditions from each chamber of the said series and again in this latter case it is convenient to take the gas from the narrow pipe forming the upper exit of each such chamber. Whether the instrument is placed within the chamber or is outside of it, though connected in either case to receive vapor laden gas therefrom, the important thing is to ascertain the value of the vapor content of the gas at a representative point so that the value ascertained may be a reliable index of the condition of the gaseous mixture in the neighborhood of the jet. This point may, of course, be close to the jet or wherever experiment shows to be satisfactory.

When the katharometer is situated outside the spinning chambers, it is possible to employ one katharometer for testing the gas alternately from two or more such chambers by suitably arranging the pipes conveying the gas so that the gas from one or other chamber can be conveyed to the katharometer as desired.

The apparatus which has been described above under the name "katharometer" is described in the specification of British Patent No. 124,453, and in U. S. Patent 1,304,208. This name is also used in connection with the specific apparatus in the "Proceedings of the Royal Society" 1920, volume 97, page 273.

The drawing accompanying this specification illustrates in vertical cross-section apparatus according to this invention. In the said drawing A represents the spinning chamber, B the nozzle containing small holes through which the solution of the cellulose derivative is extruded, C is a hole at the lower end of the spinning chamber through which the thread D passes on to the roller E. Air is drawn into the chamber A through the hole C, and out through the duct F, which is provided with an adjustable valve G, by means of which the quantity of gas passing through the chamber may be regulated. The tube H is provided with its open end in close proximity to the spinning nozzle B, while the other end is attached to the katharometer K. A further tube L attached to the katharometer is provided, and by applying a gentle suction to the tube L, vapor-laden gas is drawn from the proximity of the spinning nozzle B through the tube H into the katharometer, which can be so calibrated as to indicate the percentage of solvent vapor contained in the gas.

What we claim is:

1. The method of gaining uniformity of product in the manufacture of artificial silk by forming, in the presence of a heated gas, a jet of a cellulose derivative contained in

a volatile solvent whereby the solvent vaporizes giving a vapor content to the heated gas, the steps of the method being the ascertainment of the value of the vapor content of the gas at a point that is representative of the condition of the gaseous mixture in the neighborhood of the jet, and a maintenance of the said content at a uniform value by regulating the supply of gas to the spinning chamber.

5 2. Apparatus comprising a spinning chamber for the manufacture of artificial silk, means therein for forming a jet of a cellulose derivative contained in a volatile solvent, a duct for delivering therefrom the gas laden with vapor from the solvent, means for regulating the supply of gas passing through said chamber and means for ascertaining the value of the vapor content of said gas at a point that is representative of the conditions of 15 the gaseous mixture in the neighborhood of 20 the jet.

3. Apparatus comprising a spinning chamber for the manufacture of artificial silk, means therein for forming a jet of a cellulose derivative contained in a volatile solvent, a duct for delivering therefrom the gas laden with vapor from the solvent, means for regulating the supply of gas passing through said chamber and a katharometer connected to 25 receive vapor laden gas from a point that is representative of the condition of the gaseous mixture in the neighborhood of the jet.

In testimony whereof we have signed our names to this specification.

25 FRANK SHEDDEN.
